UNITED STATES PATENT OFFICE.

HAROLD L. DE LISLE, OF CHICAGO, ILLINOIS.

DISPENSING DEVICE FOR SHEET MATERIAL IN ROLLS.

1,409,363.

Specification of Letters Patent. Patented Mar. 14, 1922.

Application filed May 20, 1921. Serial No. 471,114.

To all whom it may concern:

Be it known, that I, HAROLD L. DE LISLE, a citizen of the United States, residing at Chicago, in the county of Cook and State of Illinois, have invented certain new and useful Improvements in Dispensing Devices for Sheet Material in Rolls, of which the following is a specification.

The present improvements relate to means for holding a plurality of rolls of thin and flexible sheet material whereby the principal objects of cleanly and safe preservation of the material and the easy and convenient withdrawal of such thereof as may be desired from time to time may be attained.

My copending and allowed application Serial No. 377,509 filed April 29, 1920 illustrates a filing cabinet provided at its upper end with a relatively small auxiliary cabinet having means for holding rolls of blue print paper, tracing paper, etc. The accompanying drawings are to be understood as showing fragmentarily the upper end portion of such a larger cabinet, and, while in its general aspect the present application is similar to my said copending application, I have shown herein the roll-holding and material-dispensing features in an improved and preferred construction.

In these drawings, Figure 1 is a top plan of the cabinet; Fig. 2 is a similar view with the top cover removed; and Fig. 3 is a vertical transverse section as on the line 3—3 of Fig. 2.

The present improvements comprise or are included within the relatively small cabinet A well outlined in Fig. 3. It has a top wall 10, a bottom wall 11, a rear wall 12, a front wall 13 and a pair of outer side walls 14. The cabinet thus defined is relatively long in the horizontal directions so as to accommodate relatively long rolls of blue print paper, tracing paper, tracing cloth or similar thin and flexible material in sheet form. Cabinet A is also relatively low in the vertical directions. In my practice it is made as a unitary structure except as to the top wall 10 and the front wall 13, which are also parts of the larger cabinet B, and this unitary structure is secured in the top portion of the larger cabinet B as shown.

The top wall 10 has a hinged door 15 through which the rolls 16, 17 and 18 of thin and flexible material may be inserted into or removed from the device.

Between the outer side walls 14 there are two intermediate walls 20 which have substantially the same shape as the outer side walls 14. These inner side walls 20 are rigidly secured to the bottom wall 11 and to the rear wall 12, as are also the outer side walls 14, a space being provided between each inner side wall 20 and the adjacent outer side wall 14. At a somewhat upper and rear location in the cabinet a rod-like member 22, in my practice a round wooden bar, is secured rigidly to the inner side walls 20 and at a middle upper portion of the cabinet the rod 23, in my practice a piece of metal tubing, is similarly held by and between the inner side walls 20. These rods 22 and 23 are substantially parallel with the axes of the rolls 16, 17 and 18.

At a somewhat forward portion of the cabinet the vertically positioned wooden strip 24 is secured rigidly between and held by the inner side walls 20. Two rests or supports 25, in my practice metal tubing, extend from the rod-like member 22 forward to the strip 24.

It is thus clear that the bottom wall 11 and the rear wall 12 of the smaller cabinet carry the inner side walls 20, and that these in turn carry the several parts 22, 24 and 25, the last three constituting a frame which supports the rolls of sheet material, this frame extending downwardly and forwardly whereby the roll as 16 will rest against the front strip 24, the roll 17 resting against the roll 16 and the roll 18 resting against the roll 17, the several rolls being held loosely and by gravity in frictional contact with each other. The roll-holding or supporting device thus accommodates various and varying size of rolls without adjustment and without prejudice to the advantages of the arrangement.

I also provide a swinging door 26, in my practice a piece of wooden board material, which carries at each end at right angles to its longitudinal direction a triangular-shaped sheet metal arm 27 which extends to the lower rear corner of the cabinet between the side walls 14 and 20 and is there pivoted by a screw at 28 to the side wall 20. The board or door 26 may therefore swing upward into its dotted line position shown in Fig. 3, exposing a relatively long and narrow opening in the lower front portion of the cabinet sufficient to permit a hand to be inserted for picking up one or another of

the end portions of the sheet material lying adjacent to the opening on the bottom 11. The side walls 14 and 20 have their front edges cut on an arc to correspond with the 5 movement of the door 26, as well illustrated in Fig. 3.

The rod-like members 22 and 23 are sheet-deflecting devices and are employed so as to enable a direct pull to be made upon any 10 particular piece of the sheet material at the door opening in front for drawing some of the material off of a particular roll for use, and to cooperate in providing an arrangement whereby a pull upon the material of one roll will not cause the material of another roll to come along with it. From Fig. 15 3 it will be observed that the material from the rearmost roll 18 is first carried over the deflector 23 and thence over the deflector 22; 20 that thereupon the material of the roll 17 is laid upon the material from the roll 18, and finally the material from the roll 16 is laid upon the material from the roll 17, these 25 three plies of the material passing partially around each of the deflectors 23 and 22 in sequence, and the plies extending forward to the discharge door opening.

Suppose now it be desired to withdraw some of the material from the roll 18. A 30 pull upon the material of that roll, namely, the topmost ply near the door 26, will naturally result in a tendency to pull along with it the material of the second or middle ply, owing to the frictional contact between 35 the two. This does not take place, however, for it will be noted that a pull upon the top-ply material extending from the roll 18 will turn that roll in an anti-clockwise direction as viewed in Fig. 3, while the frictional 40 tendency to pull off simultaneously some of the material from the adjacent roll 17 tends to move that roll in the same anti-clockwise direction. The result is that these rolls move in opposite directions where they contact each other and the friction there developed is sufficient to prevent the material from the roll 17 from coming out of the cabinet when a pull is made upon the material of the roll 18.

50 For the same mechanical reasons, whichever strip is pulled upon at the discharge opening the material from that roll only comes out.

The upwardly-and-downwardly swinging board 26 has been described herein as a door, and it has the function of closing the discharge opening of cabinet A when the door 30 of cabinet B is open. The board or door 26 has, however, a further important function. 55 Its lower edge at 31 is planed straight and constitutes a "straight-edge." This straight-edge portion of the door 26 at 31 overlaps the front edge of the bottom 11 at 32 to a limited extent whereby a portion of the bottom edge at 32 is exposed below the edge

31. This construction and arrangement are provided to facilitate the separation from the sheet material within the cabinet of that part thereof which has been withdrawn for use. In operation the door 26 is first lifted 70 sufficiently to enable the hand to select the material to be withdrawn and the desired amount of material is then simply pulled out. Thereupon the door 26 is allowed to descend, and in doing so it clamps the material between the closely contiguous overlapped parts 31 and 32, and thereupon, if the strip material be paper, it may simply be torn off, and with a clean edge, while, in the case of such material as tracing cloth, 75 a knife blade may be passed along the straight-edge 31, cutting off the material against the bottom edge 32.

In order to facilitate the selection of the material to be withdrawn I provide the recess 34 in the front edge portion of the bottom 11 at which the several plies may be conveniently fingered.

The construction thus illustrated and described is quite simple and yet provides the 90 desired safe and cleanly storage of the sheet material while enabling it to be withdrawn for use as desired in an exceedingly simple, easy and expeditious way.

Various modifications and departures 95 from what is herein specifically illustrated and described are contemplated by me as being within the invention herein set forth, as indicated in the appended claims.

I claim:

1. A holder for rolls of thin and flexible sheet material comprising in combination means for supporting a plurality of such rolls side by side in frictional contact with each other, and a rod-like sheet-material-deflector spaced from and extending substantially parallel to the axes respectively of the rolls when normally positioned on said supporting means.

2. The combination of walls forming a 110 cabinet having an opening through which relatively wide sheet material may be drawn, means within the cabinet for supporting side by side a plurality of rolls of thin and flexible sheet material and a sheet-deflecting device extending substantially parallel to the axes of the rolls when normally positioned on said supporting means, the arrangement being such that sheet material from each of said rolls may pass partially around said deflecting device, with one sheet upon another, and extend therefrom to said opening.

3. The combination of walls forming a 125 cabinet, means within the cabinet for supporting loosely side by side against each other a plurality of rolls of thin and flexible sheet material, the cabinet having an opening through which such sheet material may be drawn for use, a pair of rod-like sheet 130

- deflecting devices extending substantially parallel to the axes of such rolls when normally positioned on said supporting means, said deflecting devices being so positioned 5 that sheet material from any and all of the rolls on said support may extend partially around the one of said deflecting devices and then extend to and pass partially around the other thereof and extend thence to said opening.
4. The combination of walls forming a cabinet, downwardly-and-forwardly-inclined means within the cabinet for holding side by side against each other a plurality of rolls 10 of thin and flexible sheet material, the cabinet having a lower front opening through which the sheet material may be drawn, an upwardly - and-downwardly - swinging door for said opening, the lower edge portion of 15 said door being substantially straight and overlapping a closely contiguous part of the cabinet where the sheet material issues therefrom whereby when said door is in such overlapped relation such sheet material may be 20 clamped between the door and said contiguous part and be held while the exposed part of the sheet material is severed from the part thereof remaining within the cabinet, a rod-like sheet-deflecting device positioned above and substantially parallel to the axes 30 of such rolls when normally positioned on said roll-holding means, and a similar sheet-deflecting device positioned normally rearward of the rolls.
5. The combination of top, bottom, side, 35 front and rear walls forming a cabinet relatively wide in the horizontal directions and relatively low in the vertical directions, means within the cabinet for supporting side by side a plurality of rolls of thin and flexible sheet material, the front wall of the cabinet having a relatively long and narrow opening through which such sheet material may be drawn for use, a relatively long and narrow swinging door for the front opening, 40 said door being arranged to clamp projecting sheet material for severing the same, the top wall also having an opening and a door for same.

HAROLD L. DE LISLE.
